SHOE

Judith Leah Farrar, 2106 S. Santa Fe, Wichita, Kans.

Filed May 4, 1964, Ser. No. 79,781

Term of patent 3½ years

(Cl. D7—7)

FIG. 2

FIG. 1 is a top plan view of a shoe showing my new design; and

FIG. 2 is a side perspective view thereof, the side opposite being substantially similar thereto.

I claim:

The ornamental design for a shoe, substantially as shown and described.
